BOAT FENDER OR SIMILAR ARTICLE

John W. Duckett and Clarke Reynolds, Tiburon, Calif.,
assignors to American Molded Products, Ltd., a lim-
ited partnership, Sausalito, Calif.

Filed Apr. 28, 1969, Ser. No. 16,917

Term of patent 14 years

Int. Cl. D12—14

U.S. Cl. D71—1

FIG. 1 FIG. 2

FIG. 1 is a side elevational view of a boat fender or similar article showing our design;

FIG. 2 is a top plan view; and

FIG. 3 is a sectional view taken in the direction of arrows 3—3 in FIG. 1.

We claim:

The ornamental design for a boat fender or similar article, substantially as shown.
